UNITED STATES PATENT OFFICE.

WILLIAM SCHMOEGER, OF RUSSELLVILLE, MISSOURI.

WIRE-STRETCHER.

1,204,076.

Specification of Letters Patent.

Patented Nov. 7, 1916.

Application filed December 31, 1915. Serial No. 69,585.

To all whom it may concern:

Be it known that I, WILLIAM SCHMOEGER, a citizen of the United States, residing at Russellville, in the county of Cole and State 5 of Missouri, have invented certain new and useful Improvements in Wire-Stretchers; and I do hereby declare the following to be a full, clear, and exact description of the invention, such as will enable others skilled 10 in the art to which it appertains to make and use the same.

This invention relates to wire stretchers specially designed for use in stretching fence wires and for similar usage.

15 The invention has for its primary object to provide a similar and efficient wire stretcher of the ratchet type embodying essentially a pair of spaced ratchet bars having teeth formed upon the adjacent longitudinal edges thereof and a stretching mechanism including an operating lever and a pair of pawls pivotally secured thereto and arranged between the ratchet bars.

With this and other objects in view, the 25 invention consists in the novel construction, arrangement and formation of parts as will be hereinafter specifically described, claimed and illustrated in the accompanying drawing, in which:

30 Figure 1 represents a side elevation, partly broken away, of the improved wire stretcher, Fig. 2 represents a transverse sectional view on the line 2—2 of Fig. 1, Fig. 3 represents a fragmental side elevation, partly in section, of the stretcher, and Fig. 4 represents a transverse sectional view on the line 4—4 of Fig. 3.

Referring to the drawing in detail, wherein similar reference numerals designate corresponding parts throughout the several views, the numerals 5 and 6 indicate a pair of ratchet bars having inwardly directed teeth 7 and 8 formed upon the inner longitudinal edges thereof and connected at one 45 end by a connecting member 9, which latter may be secured to the bars 5 and 6 formed integral therewith. A ring 10 is fastened to the connecting member 9 and is associated with an anchoring chain 11, whereby the 50 wire stretcher may be anchored in position for use. The opposite extremities of the ratchet bars 5 and 6 are connected by a pair of spaced straps 13 to which is connected an auxiliary anchoring chain 11a.

55 A pair of friction reducing rollers 14 are rotatably secured in spaced relation be-

tween the straps 13 and the ratchet bars 5 and 6 upon relatively short shafts 15. A slide rod 16 is slidably mounted between the straps 13 and the friction reducing rollers 14 and is formed at its outer ends with an aperture 17 adapted to receive a chain 18 for connection with a wire or other article to be stretched and is pivotally connected at its inner extremity by a bolt 19 between 60 a pair of strips 20, arranged upon opposite sides of the bars 5 and 6 and constituting a part of the operating lever for the wire stretcher. The other part or section of the lever is designated by the numeral 22 and 65 is pivotally connected between the extended ends of the strips 20 by a pivot pin 23, whereby the handle or outer section of the lever may be folded against the bar 5 for convenient transportation. The section 22 70 is rigidly secured in alignment with the strips 20 by a removable pin 24 engaging in apertures formed in the strips 20 and section 22.

A pair of alternately operating pawls 25 80 are pivotally secured between the lever sections 20 upon opposite sides of the pivot pin 19 by pivot pins or bolts 26a. Each pawl includes a pair of arms 25a, rigidly connected at one end by a connecting pin 85 26, which latter is normally retained in engagement with the teeth of the ratchet bar by the tension of a spring 27 connecting pins 27a carried by the opposite extended ends 28 of the pawls 25.

90 A pair of guard members 29 are pivotally secured upon the pivot pins or bolts 26a, are curved from end to end and arranged with their convex surfaces disposed adjacent the teeth of the ratchet bars 5 and 6 so as to 95 prevent accidental engagement of the pivot pins 26 in the teeth 7 or 8 of the ratchet bars 5 and 6. The pins 26 carried by the pawls 25 are extended laterally of one side of the pawl, as indicated at 30, to provide handles 100 whereby the free ends of the pawls may be moved together against the tension of the spring 27 to facilitate adjustment of the slide bar 16 and the parts associated therewith.

105 In use, the wire stretcher is anchored in operative position by securing the anchoring chain 11 to a stationary object, such for instance as a tree or post, and the chain 18 is connected with the wire to be stretched. 110 By oscillating the lever 22, the slide rod 16 is caused to move inwardly between the

ratchet bars 5 and 6 by the alternate engagement of the two pawls 25 with the teeth of the two rack bars 5 and 6.

What I claim is:

A wire stretcher including a pair of ratchet bars having ratchet teeth formed upon the adjacent longitudinal edges thereof, a pair of lever sections arranged upon opposite sides of said ratchet bars, pins connecting the said lever sections and arranged between said rack bars, pawls pivotally se-

cured to said pins, and curved guard members pivotally secured to said pins adapted to prevent engagement of said pins with the teeth of said ratchet bars.

15 In testimony whereof I affix my signature in presence of two witnesses.

WILLIAM SCHMOEGER.
